(57) **CLAIM**

The ornamental design for a lamp, as shown and described.

DESCRIPTION

1. Lamp
- 1.1 : Perspective
- 1.2 : Front
- 1.3 : Back
- 1.4 : Top
- 1.5 : Bottom
- 1.6 : Left
- 1.7 : Right

The broken lines in the drawings illustrate portions of the lamp which forms no part of the claimed design.

The break lines in figures indicate that the appearance of any portion of the lamp between the break lines forms no part of the claimed design.

1 Claim, 7 Drawing Sheets
